UNITED STATES PATENT OFFICE.

ROBERT NIEDERMANN, OF BONNDORF, GERMANY, ASSIGNOR TO MATTHÄUS BEHRINGER, OF WELLENDINGEN, BADEN, GERMANY.

APPARATUS FOR DENTAL SURGERY.

Application filed September 12, 1924, Serial No. 737,400, and in Germany November 2, 1923.

This invention relates to improvements in apparatus for dental surgery.

It is an object of the invention to provide an apparatus by means of which the 5 obnoxious conditions resulting from the injection of a local anæsthetic into the jaw are relieved or entirely eliminated.

Another object of the invention is to provide an apparatus of this character in which 10 the nerves adjacent the point of injection are artificially stimulated to accelerate the return of these nerves to normal condition.

It is also an object of the invention to provide an apparatus of this character in 15 which the circulation of the blood adjacent the point of injection is reestablished immediately after the operation has been completed, in order to discharge through this circulation of the blood the injected anæsthetic immediately from the affected portions.

It is furthermore an object of the invention to prevent the symptoms of local inflammation and of pain which are due to the 20 combination of the injected anæsthetic with the blood, and to eliminate the necessity of flushing out the affected portion with some special sterilized fluid or the like.

With these and numerous other objects 25 in view, an embodiment of the apparatus for carrying out the method of stimulating the nerves is described in detail in the following specification, in which reference may be had to the accompanying drawings.

In the drawings:

Fig. 1 is an elevation of a casing containing the principal elements of the apparatus;

Fig. 2 is an elevation and partly sectional view of an electrode which is to be used in connection with the apparatus;

Fig. 3 is a front view of a portion of this electrode;

Fig. 4 is a cross-sectional view on line 4-4 of Fig. 3, the electrode illustrated in Figs. 2, 3 and 4 being specifically intended for the treatment of the upper jaw;

Fig. 5 is a view similar to Fig. 2 showing an electrode for the treatment of the 50 lower jaw;

Fig. 6 is a side elevation of an electrode and partly in section for application to the outer surface of the jaw, and

Fig. 7 is a front view of the electrode 55 illustrated in Fig. 6.

The principal instruments of the apparatus are mounted within a casing *a* which is shown here as having the outer form of a tooth which utilizes the crown as a basis. In this casing *a* are mounted an induction 60 coil *b* and a dry battery *c*, the individual elements being readily removable for repair or exchange from the casing. Conductors extend from the secondary of the induction coil to two electrodes which are in the 65 operation utilized in pairs. One of these conductors may for instance lead to the electrode indicated in Figs. 2, 3 and 4 and which is intended for application to the inner surface of the upper jaw. This electrode comprises an insulated handle *h* having a central longitudinal bore *i* through which the conductor from the secondary of the induction coil extends. Instead of passing the conductor through the bore in the 70 interior of the handle, the end of the conductor may be provided with an attachment fixture by means of which an electric conductive connection may be established between this conductor and a straight wire or 75 bar which is fixedly located in the interior of the handle *h*.

The electrode proper comprises a metallic member *d* which is bent into proper form, similar to other dental instruments 80 intended to work on the teeth of the upper jaw, and this electrode may also terminate in an attachment fixture whereby it may be brought into electric conductive connection with the conductor permanently associated 85 with the handle to complete the line of circuit from the conductor *i*, extending from the secondary of the induction coil, to the metal portion *d*. The electrode terminates in a head *e* which is properly shaped 90 to engage over a relatively large surface portion the inner surface of the jaw.

In the use of this electrode it may be advisable to attach to this head portion *e* a small pad of absorbent cotton or the like 100 to soften the pressure at which the electrode may be forced against the jaw. For the purpose of facilitating the attachment of this pad and for retaining the same in proper position on the electrode, an S-shaped hook 105 *f* traverses the neck portion of the electrode *d* and is bent in opposite directions at the projecting ends.

The electrode illustrated in Fig. 5 is constructed similar to that shown in Figs. 2, 110

- 3 and 4 inclusive and also comprises a handle σ of insulating material having in its interior a bore p which may receive an extension of a conductor or which may permanently receive a longitudinal metallic element having at its ends attachment fixtures adapted for cooperation with companion fixtures at the ends of the conductor and of the electrode respectively. The electrode illustrated in Fig. 5 is primarily intended for use on the inner surface of the lower jaw and is therefor shown as having the characteristic curvature of dental instruments serving for operations at this part of the mouth. The electrode k also terminates in a suitable head portion l and is advisably provided with a hook n , similar to the retaining element f which is used in combination with the first described electrode.
- 20 The electrode illustrated in Figs. 6 and 7 also comprises a handle portion s made preferably of insulating material and having either a bore f' through which the conductor may extend, or being provided with a longitudinal metallic element in the interior of the handle provided with attachment fixtures for receiving companion fixtures of a conductor and an electrode plate respectively.
- 30 This electrode is provided with a head portion y , preferably consisting of nickel-plated sheet copper and bent so as to engage snugly a relatively large portion of the outer surface of the jaw when suitably applied thereto. The attachment of this electrode plate y to the handle s may be effected by plug or socket connection, similar to the attachment which has been referred to above in connection with the electrodes and conductors respectively.
- 40 The operation will be understood from the above description. Immediately after the extraction of a tooth or after the completion of any other operation which took place under a local anaesthetic, one of the electrodes, as for instance the electrode illustrated in Figs. 2, 3 and 4 or the electrode shown in Fig. 5, is applied to the inner surface of the jaw at the point at which the nerves were deadened through the injection of the anaesthetic. The companion electrode shown in Fig. 6 is then placed in opposition thereto on the other surface of the jaw and a circuit is then completed through the battery and the primary of the induction coil, since the circuit through the secondary is completed by way of these electrodes and the portion of the jaw which is located between these electrodes. The outer as well as the inner electrodes are slowly reciprocated near this affected portion for about one or two minutes for the purpose of causing a thorough passage of the current through the

affected part, a stimulation of the nerves surrounding the affected portion. This stimulation initiates the circulation of blood and the injected anaesthetic is flushed out together with the blood from the puncture which has been made for the purpose of injection.

65 The present invention makes use of the well known fact that certain parts of the human body are stimulated by electricity and the present apparatus makes use of this fact for the purpose described. The anaesthetic is immediately ejected by the restoration of the circulation and the numbness, 70 which is a disagreeable sensation for the patient, is greatly relieved.

75 The invention also renders it possible thereby to make use of larger quantities of local anaesthetics than have been used heretofore and it is a very well known fact that a complete painless extraction of teeth or other painless operations cannot be carried 80 out when a small quantity only of the anaesthetic is injected.

85 I claim:

1. A pair of electrodes for use in dental surgery comprising one electrode connected to the positive terminal of a source of current supply and the other electrode connected to the negative terminal of the source of current supply, each electrode being provided with an insulated handle having a conductor extending therethrough, one of the electrodes having a suitable contact head formed at the end of its conductor for use on the inner surface of the jaw, and the second electrode having an elliptical shaped contact for use on the outer surface of the jaw, the electrodes being respectively placed on the inner and outer surface of a selected portion of the jaw for completing a circuit through the jaw to stimulate the circulation 100 in the said selected portion of the jaw.

90 2. A pair of electrodes for use in dental surgery for stimulating the circulation through a selected portion of a jaw comprising one electrode having an insulated handle, a conductor extending through the handle, a suitable contact head at one end of the conductor for contacting the inner surface of the jaw, means adjacent the head for receiving and holding a swab of cotton 105 about the contact head, the second electrode comprising an insulated handle, a conductor extending through the handle, and an elliptical shaped contact at one end of the conductor for contacting the outer surface of the 110 jaw, the electrodes being respectively placed on the inner and outer surface of the 115 jaw for completing a circuit through the jaw.

120 In witness whereof I affix my signature.

ROBERT NIEDERMANN,
